WEIGHTED CASTING FLOAT

John Gano Winter, Washington, D. C.

Application January 29, 1941, Serial No. 376,548

6 Claims. (Cl. 43—52)

This invention relates to fishing tackle and more particularly to a casting float and release especially adapted for casting lure and line in comparatively shallow water or where the fish are near the surface.

This invention is especially useful to anglers where it is necessary or desirable to cast the hooks or lure a considerable distance without the annoyance of fouling the line and lure, and to suspend the hooks or lure clear of the bottom. Accordingly one of the main objects of the invention is to provide an improved casting float and release of the above general character which will be reliable in use and operable with a minimum of effort.

Another object is to produce a casting float weighted sufficiently at one end to cast well, with stabilizing means on the other end to insure true flight without twisting and which, when in the water, will float upright with the hooks or lure at the desired depth.

Another object is to produce a device of the character described with an attachment which will prevent tangling or fouling of the leader and the line when casting.

A further object is to produce an improved weighted casting float having relatively few parts, which may be inexpensively manufactured and easily assembled.

A still further object is to produce a novel device and its anti-line and leader fouling attachment of the character described of durable and simple construction which may be easily and quickly attached or removed as desired.

Other objects will be in part obvious from the annexed drawing and in part hereinafter indicated in connection with the following analysis of this invention.

This invention accordingly consists in the features of construction, combination of parts, and in the unique relation of the members and in the relative proportioning and disposition thereof, all as more completely outlined herein.

To enable others skilled in the art fully to comprehend the underlying features of this invention and the numerous modifications in structure and relation contemplated thereby, a drawing depicting the various possible embodiments of the invention has been annexed as part of this disclosure, and in such drawing like characters of reference denote corresponding parts throughout all of the views, in which—

Fig. 1 is a view of the complete device with release clip assembled for use on a casting rod;

Fig. 2 is a longitudinal sectional view of the casting float;

Fig. 3 is a longitudinal section side view of the clip;

Fig. 4 is a front elevation of the clip; and

Fig. 5 is a view of the device floating in water. 60

Referring now to the drawing, it will be noted in Fig. 2 that the float comprises several parts: a body 1, a head 2, a core 3, a tail ring 4, a tail cap 5, and stabilizing means such as vanes 6. The body 1 has a perfectly streamlined shape with a ratio of fineness (i. e., ratio of length to maximum diameter) of about three, with the maximum diameter at about one-third of its length back from the nose and with weight 2 on the larger end. This body may be made of any suitable material such as balsa wood or cork and is here shown as being preferably solid. The head, having a concave inner face, 2 preferably of lead makes up the weighted nose of the float and is attached to the body 1 by means of a metal core or rod 3 which runs longitudinally through the head, float and tail cap 5, binding them together, and has at its opposite end a line attaching means in the form of tail ring 4.

The tail cap 5 may be a metal cone snugly fitting over the tail end of the body and serving to protect this portion from the lateral strains when casting which might otherwise cut through the body. The tail ring 4 to which the line 7 is connected may comprise simple looping of the core 3 or a conventional eye ring securely fastened to the core 3.

A plurality of stabilizing vanes 6 are equidistantly spaced around the smaller or tail end of the body 1 and run parallel to the axis. These vanes are preferably made of plastic, such as Celuloid, and fastened to the body in any of various ways depending on the composition of the float. With a balsa wood body portion, for example, it has been found these vanes 6 may be rigidly held in place in slots 9 cut into the body by waterproof cement. If a molded plastic is used for the body, these vanes may be made integral.

From experience it has been found that excellent results are obtained from a float about seven inches long and weighing about six ounces, although with a rod such as used in surf fishing, a nine-inch float weighing twelve ounces could be cast several hundred feet.

As shown in Fig. 1, the float 1 and release clip 11 are assembled on a conventional casting rod 10 having a reel 17 associated in the preferred position and relation for casting. The clip 11, which will be described in more detail below, is loosely attached at one end by suitable flexible means such as cord or wire 12 near a point 13 about three feet from the tip of the rod. The leader ring 15 shown in detail in Figs. 3 and 4 to which both the leader 8 and the line 7 are fastened snaps lightly into the clip 11. The line 7 from the leader ring 15 to the tail ring 4 should be of such a length that a loop will be formed having a depth almost equal to the length of the leader 8.

Figs. 3 and 4 show in detail the construction

of the release clip with leader ring 15 in retained position for casting. The clip comprises a narrow metal strip or plate 21 with a hole 18 for the fastening cord 12 at one end and a rectangular slot 19 cut near the other end. A spring wire latch 20 permanently secured or soldered to the plate 21 at 22 is angularly bent as in Fig. 3 so that when in normal position a portion is forced through the slot 19 as shown in Fig. 3. When the leader ring 15 is jerked from the clip 5 in casting, the latch wire 20 moves upwardly from the slot under the strain on the line thereby releasing the ring leader and lure 16.

Fig. 5 shows the position of casting float in water, that is, upright with approximately a third of its length above the surface. When a fish is hooked, the float pulls over on its side or submerges in the conventional manner, thus indicating a catch.

By this casting float and release clip, means are provided for casting hooks or lure great distances without fouling the hook on the ground, in the line, or the person casting. In shallow water or where fish are very near the surface, the clip may be dispensed with by attaching the leader and end of the line directly to the tail ring 4. The float, being perfectly streamlined and held in line of flight by its vanes with both the leader line and line secured to its tail ring, has many advantages over a casting plug where the leader and line are attached, respectively, to the opposite ends of the plug. When lines and leader attached to the opposite ends of a casting plug, the lines often become entangled in each other and great difficulty is experienced in placing the plug in the water where desired or in casting it considerable distance because of its erratic flight.

The person casting with this tackle sweeps his rod in an arc either overhead or to the side. The casting float, by reason of its weighted nose, shoots out tangentially as the result of centrifugal force, paying out the line from the reel and pulling the hook and lure after it but clear of the line. A moment after the float starts its flight, the pull of the float jerks the leader ring from the clip, thereby preventing the hooks or lure catching on obstructions or the person casting.

When the casting float lands in the water, it floats in an upright position and the lure is suspended a few feet below the surface at a depth predetermined by the length of the leader and line from the float. With knowledge of the depth of water, the length of the leader and line from the float is such as not to expose the lure to vegetation or mud on the bottom but to suspend the lure at a depth where the fish are feeding.

It is thus seen that the present invention comprehends a simple, reliable and efficient tackle especially designed for casting a lure great distances with a minimum effort and maximum dependability. It is very useful in relatively shallow water or where fish are near the surface when one wishes to place the bait well clear of the boat or bank with the assurance that the hook will be at the desired depth.

Without further analysis the foregoing will so fully reveal the gist of this invention that others can by applying current knowledge readily adapt it for various applications without omit-

ting certain features that, from the standpoint of the prior art, fairly constitute essential characteristics of the generic or specific aspects of this invention and therefore such adaptations should and are intended to be comprehended within the meaning and range of equivalency of the following claims.

I claim:

1. The combination of a fishing rod, reel, hook and line, a casting float comprising a streamlined body having a weighted nose, means thereon to connect the float at one end to the fishing line, and a clip on the rod between its ends for holding the line to the rod to prevent fouling of the line as the float is cast.

2. The combination of a fishing rod, reel, hook and line, a casting float comprising a streamlined body, a weighted nose at the larger end attached to the body by means of a metal rod running longitudinally through the body, means to connect the float to a fishing line, and line engaging means on the rod to prevent fouling of the hook and line as the float is cast.

3. The combination of a fishing rod, reel, hook and line, a casting float comprising a streamlined body with a ratio fineness of three, a weighted nose at the larger end, means comprising a metal rod running longitudinally through the float body, one end of which secures the nose in place, the other end of said metal rod forming means to connect the float to the fishing line, and means on the fishing rod to engage the line until the cast has been made, thereby to prevent fouling of the hook and line as the float is cast.

4. The combination of a fishing rod, reel, hook and line, a casting float comprising a perfectly streamlined body, a concave weighted nose at the larger end attached to the body, a rod running longitudinally through the body for holding the parts assembled, means to connect the float to the fishing line, stabilizing means on the other end of said float to keep the float in true flight, and a clip to engage the line between the float and hook mounted on the rod near its lower end to prevent fouling of the hook and line as the float is cast.

5. The combination of a fishing rod, reel, hook and line, a casting float comprising a perfectly streamlined body, a concave weighted nose at the larger end attached to the body by means of a metal rod running longitudinally through the body, means to connect the float to a fishing line at a material distance from the hook, stabilizing means on the float to keep the float in true flight when cast, and a clip near the lower end of the rod to engage the line near the hook to hold a loop in the line until the float is cast, whereby the hook may be suspended the desired distance below the surface after the cast is made.

6. The combination of a fishing rod, a reel thereon adjacent one end thereof and a line connected to the reel, with a casting float connected with the line at the free end of the rod, a combined hook and sinker and line releasing means secured at an intermediate point to the rod and adapted to engage a portion of the line between the float and hook at the time the cast is made and to release the line and hook after the cast is made by action of the float pulling on the line.
